(57) **CLAIM**

The ornamental design for extrusion for LED strip lighting, as shown and described.

DESCRIPTION

FIG. 1 is a front perspective view of a extrusion for LED strip lighting, showing the new design;

FIG. 2 is a bottom perspective view thereof;

FIG. 3 is a front view thereof;

FIG. 4 is a bottom view thereof;

FIG. 5 is another front view thereof;

FIG. 6 is a top view thereof;

FIG. 7 is yet another front view thereof;

FIG. 8 is a left side view thereof;

FIG. 9 is yet another front view thereof; and,

FIG. 10 is a right side view thereof.

The uniformly dashed lines shown in the drawings illustrate portions of the extrusion for LED strip lighting which form no part of the claimed design.
